UNITED STATES PATENT OFFICE.

HERBERT E. KAMMERER, OF LOS ANGELES, CALIFORNIA.

ELECTRICAL SWITCH BOX.

Application filed December 18, 1920. Serial No. 431,602.

To all whom it may concern:

Be it known that I, HERBERT E. KAMMERER, a citizen of the United States, residing at Los Angeles, in the county of Los Angeles and State of California, have invented new and useful Improvements in Electrical Switch Boxes, of which the following is a specification.

My invention relates to electrical switch boxes and more particularly to that type of box which is provided with a door adapted to be locked in order that access to the switch may be had only by an authorized person.

The main object of my invention is to provide a switch box of the character above described, having a suitable switch controlling handle extending outside of said box, and whereby the door thereof may not be opened until the switch has been operated to break the circuit, and said switch may not be operated to close the circuit until said door has been closed, thus preventing the switch from being operated to either open or close the circuit until the door is closed, as well as eliminating the danger of the operator receiving a shock when adjusting fuses or other parts of the mechanism.

Other objects will appear in the following description, will be pointed out in the claims, and will be embodied in the accompanying drawings, in which:

Fig. 1 is a vertical section through a switch box showing the application of my invention.

Fig. 2 is a front view of a fragmental part of the same.

Fig. 3 is a transverse section through part of the box, taken on the line 3—3 of Fig. 1, showing more clearly certain features of my invention.

Fig. 4 is a transverse section through the box, taken on the line 4—4 of Fig. 1.

Fig. 5 is a vertical fragmental section, taken on the line 5—5 of Fig. 3.

In carrying out my invention 10 represents a switch box preferably formed of sheet iron, which is provided with a swinging door 11, hinged at 12 (see Fig. 4).

Secured to the rear wall of box 10 is the insulating block 13, upon which is mounted an electrical switch 14, of usual construction, which comprises the blades 15, hinged at 16 to the terminals 17, and the contact jaws 18. The blades 15 are joined together by means of the bar 19 of insulating mate-

rial, and are adapted to be swung on hinges 16, to open or close the circuit by means of a bell crank lever 20, which is pivoted at 21 to one of the side walls of the box 10, and is provided with a rocker bar 22 at its top end, which extends transversely across said box and having a depending arm 23, which is pivoted at 24 opposite the pivot 21, to the opposite side of said box. The rocker bar 22 is connected to the blades 15 by means of a link 25, the opposite end of which being pivoted to a bracket 26, secured to bar 19.

To the lower end of lever 20 is pivoted at 27, one end of a link 28, the opposite end of which is pivoted at 29 to the lower end 30 of the operating lever 31, which is provided with a suitable handle 32. When the switch blades 15 are in a position to close the circuit, the lever 31 extends downwardly from handle 32 in substantially a vertical position for a suitable distance, and then makes substantially a right angular turn and passes into box 10 through a vertically disposed slot 33 in the door 11, the slot extending downwardly for a suitable distance and terminating in a horizontally disposed slot 34, which extends to the free edge of door 11. The lever 31 is pivoted at 35 to one of the side walls of box 10.

In order that slot 33 may be kept covered up at all times when the handle 32 is moved, a shield member 36 is pivoted to the inside of door 11 and is adapted to project over said slot and to be secured to the lever 31 by means of a notch 37 formed therein, into which said lever engages.

Pivoted to the side wall of box 10 at 38, is an upstanding bar 39 provided at its upper end with a notched flange 40, which is adapted to project under the lower end of arm 30 of lever 31, and in alignment therewith, and to be held rearwardly and out of the path of travel of the lower end of said arm against the tension of a spring 41, by means of a lug 42 secured to the inner wall of door 11, when said door is closed. The bar 39 is shielded by means of a plate 43, which is secured to the side wall of box 10 in order that it may be manipulated only by the lug 42 and spring 41.

The door 11, adjacent its lower end, is provided with a second slot 44 adapted to receive the free end of a latch member 45, which is pivoted at 46 to the outside of one of the walls of box 10, and said latch is pro-

vided with the hook 47 adapted to engage with the outer surface of said door and hold the same tightly in closed position. In order that the door 11 may be locked in a closed position against the inquisitiveness of an unauthorized person, the latch 45 is provided with a perforation 48 through which an ordinary padlock (not shown) may be passed.

10 By referring to Fig. 1 of the drawings it will be seen that when the door 11 is closed, the handle 34 may be operated from the outside of the box at will to manipulate the switch to open and close the circuit. It will also be observed that the door cannot be opened until the lever 31 is brought to a horizontal position which automatically operates the switch to break the circuit, due to the locking action of the lever 20 31 when in a vertical position.

When the lever 31 is brought to a horizontal position to permit the door to be opened, the circuit is broken, and when the door is opened the lug 42 becomes at once 25 disengaged with the bar 39, thereby permitting the spring 41 to draw said bar forwardly so that the flange 40 on bar 39 will rest under the end of arm 30, as clearly shown in dotted lines. By this construction 30 it will be obvious that the switch will be locked and cannot be manipulated to close the circuit until the door 11 is closed.

What I claim is:

1. The combination with a receptacle provided with a door and having an electrical switch mounted therein, of an operating handle pivoted in said box and adapted to project through a slot in said door to the outside of said box, means for connecting said lever to said switch, and a spring controlled latch mounted inside said box and operated by the movement of said door adapted to engage with said lever to lock the same from manipulation to close said switch when said door is open. 45

2. A safety switch, comprising a receptacle provided with a hinged cover, an electric switch mounted in said receptacle, a switch operating lever provided with a handle projecting through a slot formed in the 50 cover, a spring controlled arm mounted in said receptacle adapted to contact with the switch lever to lock the same against movement when the cover is swung to an open position, and means secured to the cover 55 for operating said spring controlled arm to disengage the same from the switch lever on a closing operation of said cover, the slot in the cover through which the switch lever projects being of such form as to prevent the opening of the door while the switch is in a closed position. 60

In witness that I claim the foregoing I have hereunto subscribed my name this 29th day of November, 1920.

HERBERT E. KAMMERER.
